CLAIM

The ornamental design for a door jam, as shown and described.

DESCRIPTION

FIG. 1 is a top perspective view of a door jam component showing my new design, the broken lines showing an extendable shaft in FIGS. 1, 2, 3 and 6 being for illustrative purposes only and forming no part of the claimed design; FIG. 2 is a left end view thereof; FIG. 3 is a front elevational view thereof, the rear elevational view being a mirror image thereof; FIG. 4 is a top plan view thereof; FIG. 5 is a bottom plan view thereof; and, FIG. 6 is a right end view thereof.
